UNITED STATES PATENT OFFICE.

SYLVAN ROSENTHAL, MORRIS SUBBER, AND HARRY A. ROSENTHAL, OF PHILADELPHIA, PENNSYLVANIA.

ROLL-CHART HOLDER.

Application filed July 27, 1922. Serial No. 577,846.

To all whom it may concern:

Be it known that we, SYLVAN ROSENTHAL, a citizen of the United States, residing at Philadelphia, county of Philadelphia, State 5 of Pennsylvania, MORRIS SUBBER, a citizen of the United States, residing at Philadelphia, county of Philadelphia, State of Pennsylvania, and HARRY A. ROSENTHAL, a citizen of the United States, residing at 10 Philadelphia, county of Philadelphia, State of Pennsylvania, have invented a new and useful Roll-Chart Holder, of which the following is a specification.

Our invention consists of a novel construction of roll chart holder. The holder is adapted to stand in the rear of a typewriter, so as to be visible to the operator, and comprises a supporting frame having mounted therein a pair of feed rollers upon 15 which feed rollers is mounted an apron or ribbon containing instructions or printed or typewritten matter for the typewriter student. Means are provided for frictionally braking or arresting the movement of said 20 rollers so that the rolls and the typewritten matter are temporarily held at any desired point, in order that the learner who is operating the typewriting machine may see the instructions and typewrite them. Pro- 25 vision is made at the upper portion of the frame for supporting a suitable chart.

Our invention further consists of other novel features of construction and advantage all as will be hereinafter fully set forth.

For the purpose of illustrating our invention, we have shown in the accompanying drawings a typical embodiment thereof which is at present preferred by us, since this embodiment will be found in practice to 30 give satisfactory and reliable results. It is, however, to be understood that the various instrumentalities of which our invention consists can be variously arranged and organized and that our invention is not limited to the 35 precise arrangement and organization of these instrumentalities as herein shown and described.

Figure 1 represents a perspective view of 40 a roll chart holder, embodying our invention, the relative position thereof with respect to a typewriter being shown, the typewriter and an additional chart being indicated in dotted lines.

Figure 2 represents a vertical partly sec-

tional view through the frictional braking 55 device for the feed rolls.

Figure 3 represents a vertical sectional view showing the opposite or right-hand bearings for the feed rolls.

Similar numerals of reference indicate 60 corresponding parts.

Referring to the drawings,

In carrying out our invention, we provide a suitable framework composed of the pair of posts or uprights 2, which are provided with the diverging feet 3, which are secured at their upper portions by a screw 4 to their respective uprights 2 and are tied together at their bottom portions by the horizontal brace 5, whose central portion 65 is secured to the lower portion of the standard 2, as indicated at 6, and its ends are secured to the feet 3 by the fastening devices 7.

About midway of the height of the standard 2, we locate the plate 8 having the outwardly extending upwardly bent portion 9 above which is located the upper feed roll 10 and the lower feed roll 11. The top edge of the upwardly bent portion 9 70 terminates in proximity to the bottom of the roll chart or instruction chart 30 to be hereafter referred to and serves to form a guide or line over which the printed instructions on the roll chart can be readily 75 read by the student, as he operates the typewriter, while the plate 8, serves to tie together the intermediate portions of the uprights 2, as is evident.

The feed roll 10 is mounted upon the 90 trunnions 12 and 13, while the lower feed roll 11 is mounted on the trunnions 14 and 15, said trunnions 12 and 14 being mounted in a vertical plate 16, in proximity to which is the braking or clamping device composed 95 of the members 17 and 18, which are held in their adjusted position by the screw 19.

The upper portion of the clamping member 17 has the concave portion 20, which is adapted to engage the upper roll 10 and 100 the lower portion of said member 17 has the concave portion 21 adapted to engage the lower roll 11.

The upper portion of the clamping member 18 has a concave portion similar to the 105 part 20 already described, which is adapted to engage the upper inner end of the roll 10 and at its lower portion is the lower con-

cave portion 23, which is adapted to engage the lower inner periphery of the lower roll 7.

The upper roll 10 is provided with the finger piece 24, which is attached to the upper trunnion 13, while the lower roll 11 is provided with the finger piece 25, which is attached to the lower trunnion 15. The trunnions 13 and 15 are mounted in a plate 26 carried by an upright 2 and the plate 26 is provided with laterally extending slots 27 which open through its front edge so that the trunnions 13 and 15 can be readily received in said slots. A vertically disposed bar 28 is secured to the plate by means of a fastening device 29, so that the trunnions 13 and 15 will be retained in assembled position with respect to said plate 26. 30 designates the chart sheet in the form of an apron or ribbon, the ends of which are wound around the rolls 10 and 11. 31 designates a cross bar connecting the uprights to form a support for an additional chart 35 which is retained in position between the flanges 32 of the angles which form the uprights and 25 the guides or keepers 33 which, as illustrated, are in the form of wires having their ends deflected and secured in a side flange of the uprights. The chart 35 is shown in dotted lines in Figure 1 and bears representation of hands with indicia, shown in part, indicative of the keys to be struck by the respective fingers. 34 is an upper cross bar. It will be apparent that any kind of a roll chart desired may be employed on the rollers 35 10 and 11 and that by revolving one roller or the other the portion on the chart will be readily visible to the student so that the proper instructions can be given without the necessity of an instructor being present. 40 The braking action on the rollers 10 and 11 can be adjusted as desired by means of the fastening device 19.

It will now be apparent that we have devised a novel and useful roll chart holder 45 which embodies the features of advantage enumerated as desirable in the statement of the invention and the above description, and while we have, in the present instance, shown and described a preferred embodiment thereof which will give in practice satisfactory and reliable results, it is to be understood that this embodiment is susceptible of modification in various particulars

without departing from the spirit or scope of the invention or sacrificing any of its 55 advantages.

Having thus described our invention, what we claim as new and desire to secure by Letters Patent, is:

1. In a device of the character stated, a 60 pair of uprights, a forwardly projecting arm carried by each upright, upper and lower rolls rotatably mounted in said arms, a roll chart carried by said rolls, a finger piece for each of said rolls for actuating 65 said chart in either direction, a horizontal bar connecting said uprights and arranged in proximity to said arms, and keepers connected to said uprights above said bar and adapted to retain a card in vertical position 70 upon said horizontal bar.

2. In a device of the character stated, a 75 pair of uprights, a forwardly projecting arm carried by each upright, upper and lower rolls rotatably mounted in said arms, a roll chart carried by said rolls, a finger piece for each of said rolls for actuating said chart in either direction, a horizontal card supporting bar, arranged above said arms and connecting said uprights, vertically disposed keepers secured to the inner surfaces of said uprights above said bar and an upper cross bar connecting the tops of said uprights, whereby a card is adapted to be retained upon said card supporting bar 85 and between said keepers and said top bar.

3. In combination, a pair of parallel posts, a cross bar at the lower end of each post, a pair of upwardly converging legs associated with each post and having their upper ends 90 connected to the respective post and their intermediate portions connected to the outer ends of the cross bar, a forwardly projecting arm carried by each post, rolls rotatably mounted in said arms, a bar connecting the posts and arranged above said arms and forming a horizontal support, and keepers connected to the posts above the last mentioned bar and adapted to retain a card in position upon said supporting bar. 95
